Application May 19, 1933, Serial No. 671,878
 Renewed February 15, 1937

12 Claims.

(Cl. 219—20)

This invention relates to air conditioning apparatus and has for its principal object the provision of new and improved apparatus of this character.

5 In the drawings accompanying this specification and forming a part of this application, I have shown, for the purpose of illustration, one form which my invention may assume, and in these drawings:

10 Figure 1 is a vertical sectional view of the invention, showing parts in elevation.

Figure 2 is a front elevational view of the invention, with portions thereof broken away to disclose the interior construction.

15 Figure 3 is a fragmentary, enlarged, broken vertical sectional view corresponding substantially to the line 3—3 of Figure 2.

Figure 4 is an enlarged fragmentary perspective view of one portion of the apparatus.

20 Figure 5 is a rear elevational view of the invention showing one manner of supporting the motor and fan unit.

Figure 6 is a similar view showing a different embodiment of the motor and fan supporting means.

25 Figure 7 is a side elevational view of a thermally responsive means employed in connection with the invention, and showing the parts in one position.

30 Figure 8 is a vertical sectional view of the thermally responsive means taken on the line 8—8 of Figure 9, and disclosing the parts in a different position.

Figure 9 is a top plan view, partially in section, of the thermally responsive means shown in Figures 7 and 8, while

35 Figure 10 is a diagrammatic layout of the electrical appliances employed in connection with the invention.

40 The embodiment of the invention shown in Figures 1 through 5, 7 through 9, and Figure 10, comprises a metallic casing 20, preferably oblong rectangular in cross-section and open at both ends. Adjacent one end of the casing 20 is dis-

45 posed a plurality of electrical heating elements 21, extending transversely across the passage defined by the inner casing wall, and, as best shown in Figures 3 and 4, each having an elongated portion 22, oblong rectangular in cross-

50 section, disposed edgewise to the direction of air flow through the casing 20, comprising a metallic outer casing 23, a heating coil 24, and interposed insulating refractory material 25, the ends of the coil being connected with terminal posts

55 26 and 27. Arranged along the body portion 22

of each heating element 21, is a plurality of laterally extending fin members 28, each having a central aperture surrounded by a flange 29, and so disposed that the flanges 29 are arranged in overlapping abutting relation, the fins 28 providing large radiating surfaces and operating also to provide air passages therebetween which direct passing air in well defined directions.

5 Supporting the heating elements 21 in proper position in the casing 20 are supporting means 10 comprising a support 30 for one set of ends of the heating elements 21, and a support 31 for the opposite ends of the heating elements 21, the supports 30 and 31 preferably being similar, though oppositely disposed, and the same reference characters designate like parts of both.

15 Each of the supports 30 and 31 comprises a pair of end blocks 32, over which is fitted an angular section 33, having a flange 34 welded to one end of the block 32, as at 35, and having a flange 36 welded to the top of the block, and the flange 36 is provided with a plurality of slots 37, each 20 beginning adjacent the corner of the section 33, and extending outwardly and opening at the free edge of the flange 36. Each slot 37 is adapted 25 for the reception of one end of the rectangular body portion 22 of an individual heating element 21, and the body portion 22 of each heating element is maintained in position in each slot 37 by means of a plate 40 detachably secured to the 30 opposite end of each block 32, as by a screw 41 tapped into the block, the plate 40 being provided with an angular flange 42 which lies snug 35 against the edge of the flange 36 and spans the mouths of the slots 37, to close the same, and the plate 40 also cooperates with the section 33, and the blocks 32, to define a hollow formation 40 characteristic of both supports 30 and 31, and within which the projecting ends of the body portions 22 of the heating elements are accommodated.

The spaced supporting formations 30 and 31 are tied together by side bars 43 having their ends secured to the blocks 32 by welding or the like, as at 44, and the side bars 43 are secured to the casing 20 by screws 45 threaded into tapped holes 45

extending through the side bars 43 and into the blocks 32. In the case of the support 31, the heating elements 21 may be inserted laterally into the slots 37, with the flange 36 extending between the adjacent end pair of fins 28, the latter preferably being placed closer together than the remainder of the fins to insure snug reception of the flange 36 therebetween, and in the case of the support 30 the heating elements 21 may also be inserted laterally into the slots 55

37, with the end fin of each, indicated at 38, spaced from the flange 36 to allow for expansion of the heating element 21; the plates 40 afterward being secured in position.

5 The projecting end portions 47 of the heating elements 21, housed within the hollow formation of the support 31, carry contacts 26 and 27, which are connected to bus bars 48 by means of angular connecting members 49, and the bars 48 in turn 10 are connected by conductors 50 and 51 with terminal posts 52 and 53 positioned in a receptacle 54 at the exterior of the housing 20, the manner of electrically connecting the heating elements 21 being hereinafter more particularly pointed out 15 in connection with the description of the dia-grammatic layout shown in Figure 10.

At the outlet of the casing 20 there are provided a plurality of louvers or deflectors 550 pivotally mounted as at 551, and manually adjustable for intercepting and directing the air issuing from the outlet of the casing 20 as desired.

At the inner side of the bank of heating elements, and within the casing 20, there is 25 mounted a partition 55 having angular flanges 56 secured to the casing wall by bolts 57, and the partition 55 is provided with a central aperture 58 within which is disposed a fan 59, carried by the armature shaft of a motor 60.

30 As shown in Figure 5 the motor 60 is supported in position with respect to the casing 20, by feet 61 projecting from the central part 62 of the motor, and the feet 61 rest upon the end portions of a plate 63, bearing upon the central 35 portions of a pair of resilient metallic supporting strips 64, the feet 61, the plate 63, and the central portions of the strips 64 being all clamped together by bolts 65, and the outer opposite end portions of the members 64 diverge 40 with respect to each other and end flanges thereof secured to the casing wall, as by bolts 66. Rubber pads may be interposed between the feet 61 and the plate 63 for dampening vibrations.

45 A somewhat different embodiment of motor mounting is shown in Figure 6, in this case comprising a supporting member having a cradle portion 67 secured by screws to the motor casing, and connected by struts 68 to a ring 69 having a flange 70 secured to the partition 55 by screws 71.

As best shown in Figure 10, the heating elements 21 are connected in parallel circuits 72, 73, and 74, the circuits 73 and 74 connecting 55 through jumper straps 75 and 76 with the conductors 77 and 78, the jumper straps in the positions shown in full lines in Figure 10, rendering the system suitable for single phase operation. The jumper straps 75 and 76 however, 60 may be rearranged, as indicated in dotted lines in Figure 10, to connect with a conductor 79, and thus render the system suitable for three phase operation. The conductors 77, 78 and 79 are adapted to be connected with feed wires 65 through a switch 80. Control mechanism is included in a parallel circuit 81, comprising a thermostatically controlled switch 82, of any commercial type, operable to make and break the circuit 81 dependent upon the temperature, 70 and operating through any well known type of switch operating mechanism, one of which may include a spring normally urging the blades of the switch 80 to disengaged position, while a solenoid 83, when energized, operates to close and hold closed the switch 80, so that when the

thermostatically controlled switch 82 breaks the circuit 81, the solenoid is de-energized, permitting the spring to disengage the switch 80 and cut off the supply of current to the heating elements 21. The motor and fan unit may be included in another circuit not affected by the making and breaking of the circuit 81.

5 My invention also contemplates the inter-position of a safety cut-out device 84, within the control circuit 81, this device being positioned adjacent the heating elements 21 within the casing 20. As best shown in Figures 1, 7, 8, and 9, the safety thermal cut-out comprises an elongated metallic block 85 secured by bolts to the plate 34 of the supporting formation 31 for 15 the heating elements 21, and to the opposite sides of the block are clamped resilient contact members 86 and 87, having angular end portions provided with contact points 88, and the member 87 is extended to provide an extension 89, and to the extension 89 is clamped an operating rod 90 extending to the outside of the casing 20 and terminating in an operating knob, each of the contact members 86 and 87 being insulated from the block 85 and from each other 25 by suitable insulating members, and the bolts 91 which clamp the contact members in position also serve as terminal members 92 for connection with wires forming the circuit 81. The block 85 is also provided with an offset portion 30 93 to which is secured a bimetallic thermally responsive element 94, and to the opposite side of the block 85 is secured a resilient latch member 95 having a screw extending laterally there-through providing an adjustable post 96 which 35 extends between the contact members 86 and 87 and into abutment with the thermally responsive element 94, and beyond the post 96 the latch member 95 is provided with a laterally extending portion having an engaging face 97 40 adapted in one position to bear against the extension 89 to hold the contacts 88 in engagement, and also having a beveled surface 98 to facilitate movement of the extension 89 into latching position when the extension 89 is moved 45 by manipulation of the rod 90 to reset the latch after the same has been detached.

Assuming the jumper straps 75 and 76 to be in the position illustrated in full lines in Figure 10, for single phase operation, and the circuit 81 closed, the fan will operate to direct air through the casing 20, and through and into contact with the heating elements 21, such air emerging between the louvers or deflectors 550. Due to the manner in which the heating elements 21 are arranged in the casing, that is, edgewise with respect to the air stream, and because of the presence of the fins 28 upon the heating elements 21, passage of the air through the heating elements not only is not unduly obstructed, but the air is directed in well defined paths forwardly from the mouth of the casing and the air so issuing may be more effectively directed where desired through manipulation of the louvers 550; in addition the fins 28 provide extensive radiating surfaces and great efficiency as will be understood. The heating elements 21 may be operated in concert, as just described, but, if desired, the heating units in the circuits 73 and/or 74 may be cut out temporarily by disconnecting the jumper straps 75 and/or 76.

Automatic control of the heating elements 21 is effected through operation of the thermostatically controlled switch 82 which interrupts the circuit 81 when the temperature rises be- 75

yond a predetermined level, resulting in disconnection of the switch 80, and deenergization of the heating elements 21. When the temperature falls sufficiently to again operate the thermostatically controlled switch 82, the circuit 81 is again closed, resulting in closing of the switch 80, and energization of whatever heating elements are included in the circuit.

The safety thermal cut-out 84 is located adjacent to the heating coils 21, and when the temperature rises too high for safety, the safety cut-out operates to interrupt the circuit 81, and deenergizes the heating elements. This operation takes place through deformation of the bimetallic strip 94, which forces the latch 95 outwardly, and causes the contact member 87 to spring away and separate the contact points 88. The safety cut-out of course deenergizes the circuit 81 until the device is reset by manipulation of the rod 90, which may be pressed inwardly, causing the extension 89 of the contact member 87 to ride along the beveled surface 98 of the latch until the latch springs into position to again hold the points 88 in engagement.

To convert the heater circuit for three phase operation it is only necessary to disconnect the jumper straps 75 and 76 from communication with the conductors 77 and 78, and connect the ends thereof to the third conductor 79, in which case the circuits 73 and 74 are completed through the conductor 79, and the remainder of the apparatus operates in the manner already described.

While I have herein disclosed the preferred embodiment of my invention it will be understood that various changes may be made and details modified, all without departing from the spirit of my invention, or sacrificing the advantages thereof, either those advantages hereinabove specifically pointed out or any other advantages not specifically pointed out but which nevertheless will be apparent to those skilled in the art. Therefore it will be understood that the disclosure herein is illustrative only, and that my invention is not limited thereto.

I claim:

1. Apparatus of the character described, comprising: a plurality of heating elements having conductors forming connected circuits; multi-phase feed conductors; and conducting means adapted to form part of said connected circuits and shiftably mounted and selectively connectable with two or more of said feed conductors in different combinations to effect different phase operation.

2. Apparatus of the character described, comprising: a plurality of electrically operable elements arranged in groups; conductors connecting said groups in parallel circuits; three-wire feed conductors; and jumper connecting means interposed in one of said parallel circuits and interchangeably connectable with the feed conductors of the other circuit, or with the third wire of said feed conductors.

3. Heating apparatus, comprising: an electrical resistor; supply conductors for said resistor; a contactor interposed in said supply conductors; electro-responsive operating means for said contactor; a thermostat, having contacts, disposed in the space to be heated by said resistor; a manually operable switch; and conducting means connecting said electro-responsive operating means and said thermostat contacts and said

manually operable switch in series in a circuit in shunt with said supply conductors.

4. Heating apparatus, comprising: an electrical resistor; supply conductors for said resistor; a contactor interposed in said supply conductors; electro-responsive operating means for said contactor; a thermostat, having contacts, disposed in the space to be heated by said resistor; thermal cut-out means, disposed adjacent said resistor, directly subject to heat given off by said resistor; and conducting means connecting said electro-responsive operating means and said thermostat contacts and said thermal cut-out means in series in a circuit in shunt with said supply conductors.

5. Heating apparatus, comprising: an electrical resistor; supply conductors for said resistor; a contactor interposed in said supply conductors; electro-responsive operating means for said contactor; thermal cut-out means, having relatively movable contacts, disposed adjacent said resistor, directly subject to heat given off by said resistor; means whereby said thermal cut-out means causes movement of said relatively movable contacts to one position in response to said heat, said contacts remaining in said position until manually reset; and conducting means connecting said electro-responsive operating means and said relatively movable contacts of said thermal cut-out in series in a circuit in shunt with said supply conductors.

6. In combination: an electrical heating element; supply conductors for said element; means including a thermally responsive device, disposed in the space to be heated by said heating element, automatically operable to connect and disconnect said heating element and said supply conductors; a motor-driven fan for directing a stream of air against said heating element; and thermally responsive safety means, disposed adjacent said heating element and subject to the combined influence of the heat given off by said heating element and the stream of air generated by said fan, and operable upon abnormal rise in temperature at said thermally responsive safety means to cause disconnection of said heating element from said supply conductors.

7. In combination: an electrical heating element; supply conductors for said element; a motor-driven fan for directing a stream of air against said heating element; thermally responsive safety means, disposed adjacent said heating element and subject to the combined influence of the heat given off by said heating element and the stream of air generated by said fan, and operable upon abnormal rise in temperature at said thermally responsive safety means to cause disconnection of said heating element from said supply conductors; and means whereby said motor-driven fan may be caused to operate while said heating element is disconnected from said supply conductors.

8. In combination: an electrical heating element; supply conductors for said element; means including a thermally responsive device, disposed in the space to be heated by said heating element, automatically operable to connect and disconnect said heating element and said supply conductors; an electric motor-driven fan for directing a stream of air against said heating element; thermally responsive safety means, disposed adjacent said heating element and subject to the combined influence of the heat given off by said heating element and the stream of air

generated by said fan, and operable upon abnormal rise in temperature at said thermally responsive safety means to cause disconnection of said heating element from said supply conductors; and means for separately feeding said motor from said supply conductors so that said motor-driven fan may continue to operate when said heating element is disconnected from said supply conductors.

- 10 9. In combination: means including a motor for producing a current of air, said current of air ceasing to flow upon stoppage of said motor; heating means disposed in the current of air whereby the current of air abstracts heat from said heating means; means for supplying energy to heat said heating means; and means whereby upon stoppage of said motor said energy supplying means ceases to supply energy to said heating means.
- 15 10. Heating apparatus connectable to electrical supply conductors, comprising: a plurality of groups of electrical heating elements, each group including one or more heating elements; means for selectively connecting a predetermined num-

ber of said groups in parallel across two supply conductors or connecting said groups individually across different pairs of supply conductors.

11. Heating apparatus connectable to electrical supply conductors, comprising: a plurality of series connected groups of electrical heating elements, each group including one or more heating elements; means for selectively connecting a predetermined number of said groups in parallel across two supply conductors or connecting said groups individually across different pairs of supply conductors.

12. Heating apparatus connectable to conductors of a single phase or three phase alternating current supply, comprising: a plurality of groups of electrical heating elements, each group including one or more heating elements; means for selectively connecting a predetermined number of said groups in parallel across a single phase supply or connecting said groups individually across different pairs of conductors of a three phase supply.

EDWIN L. WIEGAND.
